US00D654530S

(12) **United States Design Patent**
Markovitz et al.

(10) **Patent No.:** **US D654,530 S**
(45) **Date of Patent:** **** Feb. 21, 2012**

(54) **EYEGLASSES**(75) Inventors: **Aaron Markovitz**, New York, NY (US);
Artiss Akarra, Johnston, RI (US)(73) Assignee: **Cross Optical Group, Inc.**, Daytona Beach, FL (US)(**) Term: **14 Years**(21) Appl. No.: **29/383,679**(22) Filed: **Jan. 20, 2011**(51) **LOC (9) Cl.** ..... **16-06**(52) **U.S. Cl.** ..... **D16/326**(58) **Field of Classification Search** D16/101,
D16/300–342, 900; D29/109–110; D24/110.2;
351/41, 44, 51–52, 62, 158, 92, 103–123,
351/140, 153, 45–46; 2/426–432, 447–449,
2/441, 434–437, 13, 15; D21/483, 659–661

See application file for complete search history.

(57) **CLAIM**

The ornamental design for eyeglasses, as shown and described.

DESCRIPTION

FIG. 1 is a front view illustrating my design for eyeglasses;
FIG. 2 is a top view thereof;
FIG. 3 is a left side view, the right side being a mirror image thereof;
FIG. 4 is a front perspective view thereof;
FIG. 5 is a rear view thereof; and,
FIG. 6 is a bottom view thereof.
